(57) **CLAIM**

The ornamental design for a robot vacuum charging unit, as shown and described.

DESCRIPTION

FIG. 1 is a front elevation view of a robot vacuum charging unit showing our new design when the charging prongs are down;

FIG. 2 is a left side elevation view thereof showing our new design when the charging prongs are down, the right side being a mirror image;

FIG. 3 is a perspective view thereof showing our new design when the charging prongs are down;

FIG. 4 is a top view thereof showing our new design when the charging prongs are down;

FIG. 5 is a front elevation view thereof showing our new design when the charging prongs are up;

FIG. 6 is a left side elevation view thereof showing our new design when the charging prongs are up, the right side being a mirror image;

FIG. 7 is a perspective view thereof showing our new design when the charging prongs are up; and,

FIG. 8 is a top view thereof showing our new design when the charging prongs are up.

The bottom of the robot vacuum charging unit is unornamented and, therefore, not shown.

1 Claim, 8 Drawing Sheets
